LOCK

Edward N. Jacobi, Milwaukee, Wis., assignor to
 Briggs & Stratton Corporation, Milwaukee,
 Wis., a corporation of Delaware

Application May 8, 1933, Serial No. 669,858

38 Claims. (Cl. 70—46)

This invention relates to certain new and useful improvements in locks and has as a general object to provide a lock which cannot be picked by the usual methods.

5 Another object of this invention is to provide a tumbler lock which cannot be forced by an improper key or a hardened steel key.

Another object of this invention is to provide 10 a lock of the character described in which the parts upon which the security of the lock depends, are all self-contained in the cylinder assembly and are practically independent of the casing so that a close fit between the lock cylinder and the casing is obviated.

15 Another object of this invention is to provide a tumbler lock having an auxiliary tumbler which can be retracted only after the other tumblers have been bodily shifted parallel to the major axis of the lock cylinder.

20 It is also an object of this invention to further increase the security of the lock by providing means for preventing bodily shifting of the main tumblers until all of said main tumblers are fully retracted.

25 Another object of this invention is to provide a tumbler construction which will afford greater strength and having a wider engagement with the walls of the casing tumbler grooves.

30 Another object of this invention is to provide a lock of the character described wherein the tumblers comprise a self-contained unit or pack insertable as an entirety into the lock cylinder, so that delicate thin wall sections in the tumbler receiving chamber of the lock cylinder are entirely done away with.

35 And a further object of this invention is to provide a lock in which a final inward pressure must be applied to the key to free the lock cylinder for rotation.

40 With the above and other objects in view which will appear as the description proceeds, my invention resides in the novel construction, combination and arrangement of parts substantially as hereinafter described and more particularly defined by the appended claims, it being understood 45 that such changes in the precise embodiment of the hereindisclosed invention may be made as come within the scope of the claims.

45 In the accompanying drawings, I have illustrated one complete example of the physical embodiment of my invention constructed according to the best mode I have so far devised for the practical application of the principles thereof, and in which:

50 Figure 1 is a top view of a lock cylinder em-

bodying this invention and received in a casing;

Figure 2 is a view partly in elevation and partly in section taken on the plane of the line 2—2 of Fig. 1;

Figure 3 is a cross section view taken through Fig. 2 on the plane of the line 3—3;

Figure 4 is a cross section view taken through Fig. 2 on the plane of the line 4—4;

Figure 5 is a perspective view of the entire tumbler unit with its component parts separated;

Figure 6 is a cross section view similar to Fig. 3, but illustrating the key in position;

Figure 7 is a front end view of only the tumbler carrier and the stationary side plate showing the manner in which these two parts are slidably interlocked;

Figure 8 is a side view of the key;

Figure 9 is a perspective view of the lock cylinder and the tumbler unit separated, but with the tumbler unit assembled and ready for insertion into the lock cylinder;

Figure 10 is a view similar to Fig. 2 showing the key inserted and the main tumblers retracted; and

Figure 11 is a view similar to Fig. 10, but showing the key pushed in and the auxiliary tumbler retracted.

Referring now more particularly to the accompanying drawings in which like numerals indicate like parts throughout the several views, the numeral 5 represents a lock cylinder which is adapted to be rotatably mounted in the bore 6 of a casing 7. An enlarged flange 8, formed on the outer end of the lock cylinder, is received in a counterbore 9 at the outer end of the bore 6. It is observed that the lock cylinder has substantial clearance in the bore 6 throughout the major portion of its length and that only a small portion 10 directly adjacent the enlarged flange 9 has a snug fit in the bore. This comparatively large clearance is made possible without detracting from the security of the lock by reason of the novel construction of the tumbler unit indicated generally by the numeral 11.

The tumbler unit which will be defined in detail hereinafter, is inserted bodily into a tumbler receiving chamber 12 extending transversely through the lock cylinder. The chamber 12 is merely an open slot formed during the die-casting of the cylinder by a single core which is pulled from one side. As is customary, a keyway 13 extends inwardly from the front face of the cylinder to communicate with the chamber 12.

Figure 11 comprises a tumbler pack

14 including the five main tumblers 15, and an auxiliary tumbler 16 independent of the pack. The five main tumblers are held assembled by a carrier 17 stamped from sheet metal and having 5 spaced end walls 18 and 19 connected by a side wall 20. The end walls are of a width to extend across the width of the tumbler receiving chamber 12. The carrier for the pack is thus held against sidewise movement, but as the pack is 10 shorter than the chamber 12, endwise movement thereof parallel to the major axis of the lock cylinder is permitted, for a purpose to be later described.

Each of the five main tumblers has a recess 15 cut into it from one side to form spaced end portions 21 and 22 connected by an intermediate portion 23. The space between the end portions 21 and 22 serves as a recess to receive a key 24, and in different tumblers is differently 20 located to make up the combination of the lock as determined by the hills and dales of the key.

At the side of each tumbler having the intermediate portion 23 is a projecting lug 25 which is slidably received in one of a plurality of slots 26 formed in the side wall 20. The slots 26 are longer than the projecting lugs 25 so that the individual tumblers have a limited longitudinal movement with respect to the carrier. The engagement of the lugs 25 in the slots 26 serves to 30 guide the tumblers at one side.

Inasmuch as the lugs 25 do not project entirely through the side wall 20 of the carrier, it follows that the tumblers are held out of contact with the adjacent die-cast wall of the lock cylinder. 35 The projecting lugs 25 occupy the same position in all of the tumblers so that all tumblers have an equal distance of longitudinal travel.

As stated, the engagement of the lugs 25 in the slots 26 guides the tumblers and holds them 40 properly spaced along one side edge. At their opposite sides the tumblers are guided and held properly spaced by longitudinal abutting ribs 27. The ribs 27 are of such dimensions that the combined thicknesses of the tumblers at the ribs 27 45 spans the distance between the carrier end walls. Besides guiding the tumblers for individual longitudinal movement these ribs 27 also stiffen the tumblers. The strength of the tumblers is also increased by spaced ribs 28 and 29 formed at the sides of round bottomed longitudinal grooves 50 30 in the opposite faces of the tumblers.

The round bottomed grooves 30 of adjacent tumblers co-act to form longitudinal guideways in which expansive springs 31 are received. At 55 one end the springs 31 bear against tangs 32 struck from the grooved portions of the tumblers and at their other ends they bear against spring stops 33 struck inwardly from one edge of the carrier side wall 20. The spring for each tumbler is at its front face so that the spring for the foremost tumbler is confined between the round bottomed groove in said foremost tumbler and the adjacent portion of the end wall 18. To 60 accommodate this spring, the end wall 18 has its upper portion offset, as at 34.

Obviously, the action of the springs 31 yieldably urges each individual tumbler to project its end portion 22 beyond the cylindrical surface of the lock cylinder and into locking engagement 70 with one of two usual tumbler grooves 35 in the casing.

The open side of the carrier is closed by a side plate 36 which has an interlocking connection with the end walls 18 and 19 of the carrier, but 75 when inserted into the chamber 12 of the lock

cylinder, is held stationary while the carrier and the main tumblers positioned therein are movable as hereinbefore stated. This side plate 36 is stamped from sheet metal and has inwardly directed flanges 37 and 38 at its opposite side edges. The flange 37 projects into the spaces between the end portions 21 and 22 of the tumblers and forms a key guide and support adapted to enter a longitudinal groove 39 formed in one side of the key. 80

The other flange 38 of the side plate 36 has a plurality of notches cut into it to divide the same into a series of comb teeth 40 which, when the carrier and the tumblers disposed therein are in their normal positions, lie between the adjacent side edges of the tumblers to thus positively prevent bodily shifting of the tumbler pack. The end portions 41 and 42 of the flange 38 are engaged with the carrier end walls 18 and 19 respectively in a manner now about to be described. 95

The end wall 18 of the carrier has its medial portion cut away as at 43 to permit the passage of the key into engagement with the tumblers. This leaves spaced arms 44 and 44' spaced apart a distance to snugly receive the adjacent end of 100 the side plate. The other end wall 19 of the carrier is also medially cut away, as at 45, leaving an overhanging arm 46 which is notched, as at 47, to receive the flange end portion 42. Relative motion between the side plate 36 and the carrier is 105 thus restricted to the desired endwise shifting of the carrier.

With the side wall 36 properly assembled with the carrier, the entire assembly is inserted into the chamber 12 of the lock cylinder, the insertion being effected through one side of the chamber, which for convenience in description, may be considered the top. The side walls of the chamber 12 have shoulders 48 and 49 to engage the bottom edges of the side wall 20 and the side 110 plate 36, respectively, to limit the inward movement of the assembly into the chamber and properly locate the tumbler pack within the cylinder. 115

As best shown in Fig. 5, the side plate 36 has projections 50 and 51 at its outer and inner ends, 120 respectively, and these projections are received in suitable recesses 52 and 53, respectively, at the ends of the chamber 12. The side wall 36 is thus rigidly held assembled with the lock cylinder, while the tumbler pack comprising the carrier 125 and the five main tumblers, is shiftable endwise in the chamber 12.

An expansive spring 54 confined between the end wall 19 of the carrier and the end wall 55 of a recess 56 communicating with the inner 130 end of the chamber 12, yieldably maintains the tumbler pack in its normal position engaging the front end of the chamber 12. It is noted that the ends of the spring 54 are directed longitudinally to enter apertures in the carrier wall 19 and 135 the wall 55 to hold the spring against displacement.

Mounted at the inner end of the chamber 12 is the auxiliary tumbler 16. This tumbler is stamped from a flat sheet of metal and is wider 140 than the main tumblers to have its opposite side edges received in transverse grooves 57 formed in the opposite side walls of the chamber 12. These grooves 57 are open at the top, but are closed by shoulders 58 at the bottom to restrain 145 outward movement of the tumbler 16 beyond a predetermined degree. At its limit of outward movement defined by the shoulders 58, the projecting end 59 of the tumbler 16, which is of the same width as the active ends of the primary 150

tumblers, is projected beyond the cylindrical wall of the cylinder to enter one of the locking grooves 35. The opposite end of the tumbler 16 is cut away as at 60 to accommodate the spring 54.

5 The tumbler 16 is positively held in its operative projected position as long as the tumbler pack is in its normal position of endwise movement to which it is urged by the spring 54, by a cam or tail piece 61, projecting rearwardly from the carrier wall 19 and entering a central opening 62 in the tumbler 16. The cam 61 is preferably formed by the metal struck from the wall 19 in the formation of the recess 45 and has a flat outer end 63 which engages

10 the bottom wall of the opening 62 in its operative holding position. An inclined wall 64 leads upwardly from the end 63 to move the tumbler 16 to its operative position during forward endwise movement of the tumbler pack.

15 20 It is thus obvious that retraction of the tumbler 16 out of locking engagement with the groove 35 necessitates shifting the tumbler pack inwardly against the action of the spring 54. Such inward shifting of the tumbler pack, however, is positively prevented as long as the primary tumblers are in their locking positions, by reason of the inter-engagement of the comb teeth 40 with the adjacent side edges of the tumblers. These side edges of the tumblers have notches 65 which, when aligned with the flange 38 from which comb teeth 40 are cut, releases the pack for endwise shifting to enable complete release of the lock cylinder. Endwise shifting of the tumbler pack is thus possible only when all of the primary tumblers are completely retracted.

25 30 Inward pressure on the key effects the desired shifting of the tumbler pack and for this purpose the key is provided with a shoulder 66 which engages the rib 27 of the foremost tumbler as best shown in Figs. 9 and 10. Inasmuch as the ribs 27 of the primary tumblers are in abutting relation, the force applied through the shoulder 66 is transmitted directly to all of the tumblers and to the carrier in which they are

35 40 mounted. When the key has been inserted sufficiently far to retract all of the primary tumblers and to engage its shoulder 66 with the rib 27 of the foremost tumbler, the nose 67 of the key projects beyond the inner end of the carrier into the central opening 62 in the tumbler 16. The relative positions of the nose of the key and the tumbler 16 at this stage of the unlocking action are shown in Fig. 10. Upon endwise shifting of the tumbler pack by pressure on the key, the inclined edge of the nose 67 engages the top wall of the opening 62 in the tumbler and lifts the same to unlocked position.

45 50 Upon release of the inward pressure on the key, the spring 54 will immediately return the tumbler pack to its normal position, automatically moving the auxiliary tumbler 16 to its locked position through the medium of the cam 61.

55 60 From the foregoing description, it will be apparent to those skilled in the art to which this invention appertains, that to pick the lock of this invention, is extremely difficult, if not impossible. The fact that the auxiliary tumbler is positively held in its locked position until the tumbler pack has been shifted endwise and the necessity for the retraction of all of the primary tumblers comprising the pack before such endwise shifting of the pack can take place, makes

65 70 75 it practically impossible to pick the lock.

Moreover, by reason of the fact that a single member, namely, the side plate 36, serves to guide the key and also engages the tumblers to prevent endwise shifting of the pack, and the further fact that the engaging portions of the comb teeth and the tumblers have sharp acute corners, precludes the response of the lock to a key which differs, but slightly from the proper key.

80 85 The primary tumblers thus perform dual locking functions, the first being their normal locking engagement with the casing tumbler grooves and the second being effected through their inter-engagement with the comb teeth of the side plate 36.

90 95 It is also apparent that by reason of the wide edges of the tumblers, wearing into the casing grooves is materially minimized and through the provision of the sheet metal linings afforded by the side wall 20 of the carrier and the side plate 36, wearing of the tumblers into their guides is reduced to a negligible minimum.

100 105 It is also evident that as all parts concerned with the security of the lock are self-contained in the cylinder assembly, the picking protection and the protection between changes does not depend upon a close fit between the cylinder and its casing. Hence, a greater clearance is possible between the cylinder and its casing so that sticking and corrosion due to excessive friction is entirely obviated.

What I claim as my invention is:

110 115 1 In a lock, a casing, a lock cylinder rotatable in the casing, a plurality of locking tumblers in the lock cylinder yieldably projected into engagement with the casing to restrain rotation of the lock cylinder, means to mount one of said locking tumblers for bodily movement axial to the lock cylinder, said axially movable locking tumbler being retractable by the insertion of a proper key into the lock cylinder and the other locking 120 tumbler being retractable upon bodily shifting of said first mentioned locking tumbler axially to the lock cylinder by continued inward pressure on the key.

125 130 2. In a lock device including a lock cylinder, a plurality of locking tumblers, a carrier axially shiftable within the lock cylinder and holding the plurality of tumblers as an assembled pack, said tumblers being retractable by the insertion of a proper key into the lock cylinder and being shiftable with their carrier upon inward movement of the key beyond that required to retract the tumblers, and an auxiliary tumbler retractable entirely within the body of the cylinder by said additional inward movement of the key.

135 140 3. In a lock device including a lock cylinder, a plurality of locking tumblers, a carrier axially shiftable within the lock cylinder and holding the plurality of tumblers as an assembled pack, said tumblers being retractable by the insertion of a proper key into the lock cylinder and being shiftable with their carrier upon inward movement of the key beyond that required to retract the tumblers, an auxiliary tumbler retractable into the body of the cylinder by said additional inward movement of the key, and means on said carrier to hold the auxiliary tumbler in an operative position when the carrier is in its normal position, said means becoming inoperative upon said additional inward movement of the key and 145 the tumbler pack.

145 150 4. In a lock, a lock cylinder having a tumbler receiving chamber, a plurality of tumblers, a carrier for the tumblers to hold the same assembled as a unitary pack, said carrier with the

- tumblers therein being shiftable axially of the lock cylinder within said chamber, means to yieldably urge the tumbler pack toward one position of axial movement, said tumblers being retractable by the insertion of a proper key into the lock cylinder, and the entire pack being shiftable against the urging means upon inward movement of the key beyond that required to retract the tumblers, an auxiliary tumbler, and a cam on the carrier engaging the auxiliary tumbler to hold the same in its operative extended position when the tumbler pack is in its normal position, said auxiliary tumbler being retractable upon axial shifting of the tumbler pack by said additional inward movement of the key. 5. In a lock, a lock cylinder having a tumbler receiving chamber, a plurality of tumblers, a carrier for the tumblers to hold the same assembled as a unitary pack, said carrier with the tumblers therein being shiftable axially of the lock cylinder within said chamber, means to yieldably urge the tumbler pack toward one position of axial movement, said tumblers being retractable by the insertion of a proper key into the lock cylinder, and the entire pack being shiftable against the holding means upon inward movement of the key beyond that required to retract the tumblers, an auxiliary tumbler, a cam on the carrier engaging the auxiliary tumbler to hold the same in its operative extended position when the tumbler pack is in its normal position, said auxiliary tumbler being retractable upon axial shifting of the tumbler pack by said additional inward movement of the key, and means to prevent axial shifting of the tumbler pack except when all of the tumblers comprising the pack are in their fully retracted positions. 6. In a lock, a lock cylinder having a tumbler receiving chamber, a tumbler pack in said chamber comprising, a plurality of tumblers and a carrier to hold said tumblers assembled, said tumbler pack being bodily shiftable axially of the lock cylinder, means to yieldably oppose axial shifting of the tumbler pack in one direction and to hold the pack in a normal position, means engageable with the tumblers when the pack is in its normal position to prevent axial shifting of the pack except when all of said tumblers are retracted, said tumblers being retractable by the insertion of a proper key, and an auxiliary tumbler retractable by the axial shifting of the tumbler pack by said proper key. 7. In a lock, a lock cylinder having a tumbler receiving chamber, a tumbler pack comprising a plurality of tumblers and a carrier holding the tumblers assembled, said tumbler pack being shiftable axially of the lock cylinder within its tumbler receiving chamber, a member fixed with respect to the lock cylinder and having engagement with the individual tumblers to prevent axial shifting of the tumbler pack except when all of said tumblers are retracted, said tumblers being retractable by the insertion of a proper key into the lock cylinder to engage the tumblers, and the tumbler pack being axially shiftable by inward pressure on the key, and means on said fixed member to guide the key. 8. In a tumbler lock including a casing and a lock cylinder received therein, a plurality of tumblers carried by the lock cylinder and yieldably projected into locking engagement with the casing to hold the lock cylinder against rotation, said tumblers being retractable by a proper key to free the lock cylinder for rotation, means to prevent retraction of one tumbler until another tumbler has been shifted bodily in a line parallel to the major axis of the lock cylinder, and means to prevent such bodily shifting of said other tumbler until it has been retracted. 9. In a tumbler lock including a casing and a lock cylinder received therein, a plurality of tumblers carried by the lock cylinder and yieldably projected into locking engagement with the casing to hold the lock cylinder against rotation, said tumblers being retractable by a proper key to free the lock cylinder for rotation, means connected with a first tumbler and engageable with a second tumbler to hold said second tumbler against retraction until the first tumbler and said means connected with it has been shifted axially with respect to the lock cylinder, and means to prevent such bodily shifting of said first tumbler and the means connected with it until said first tumbler has been retracted. 10. In a tumbler lock including a casing and a lock cylinder received therein, a plurality of tumblers carried by the lock cylinder and yieldably projected into locking engagement with the casing to hold the lock cylinder against rotation, all of said tumblers being retractable into the body of the cylinder by a proper key to free the lock cylinder for rotation, and means requiring successive retraction and bodily flatwise shifting of one tumbler to retract another tumbler. 11. In a tumbler lock including a casing and a lock cylinder received therein, a plurality of tumblers carried by the lock cylinder and yieldably projected into locking engagement with the casing to hold the lock cylinder against rotation, all of said tumblers being retractable into the body of the cylinder by a proper key to free the lock cylinder for rotation, means to hold some of said tumblers assembled as a unitary pack, and means requiring successive retraction of the tumblers comprising the pack and a bodily shifting of the pack axially to the lock cylinder to retract another of said tumblers. 12. In a tumbler lock including a casing and a lock cylinder therein, said lock cylinder having a transverse tumbler receiving chamber, a tumbler pack mounted in said chamber so as to have bodily movement parallel to the major axis of the lock cylinder, said tumbler pack embodying a plurality of tumblers each individually spring pressed into locking engagement with the casing and all retractable by a proper key, an auxiliary tumbler separate from said pack, said auxiliary tumbler also being retractable into the body of the cylinder and a connection between the auxiliary tumbler and said pack whereby axial shifting of the pack is necessary to allow locking retraction of said auxiliary tumbler. 13. In a tumbler lock including a casing and a lock cylinder therein, said lock cylinder having a transverse tumbler receiving chamber, a tumbler pack mounted in said chamber so as to have bodily movement parallel to the major axis of the lock cylinder, said tumbler pack embodying a plurality of tumblers each individually spring pressed into locking engagement with the casing and all retractable by a proper key, an auxiliary tumbler separate from said pack, a connection between the auxiliary tumbler and said pack whereby axial shifting of the pack is necessary to allow locking and unlocking movement of the said auxiliary tumbler, and means restricting axial shifting of the pack until the tumblers of the pack have been retracted. 14. In a tumbler lock including a lock cylinder, a tumbler unit inserted bodily into an aperture 150

- in the lock cylinder comprising a carrier having spaced end walls connected by a side wall, a plurality of tumblers between the end walls and contacting each other on their adjacent faces, individual tumbler springs disposed between adjacent tumblers and confined between abutments on the tumblers and the carrier side wall, and sliding guide connections between the tumblers and the side wall. 5 80
- 10 15. In a lock cylinder, locking tumblers movable transversely of the lock cylinder, longitudinal ribs on opposite faces of the tumblers, the ribs of adjacent tumblers abutting to maintain the tumblers properly spaced, and springs between the tumblers to yieldably project the tumblers from the lock cylinder. 15 85
16. In a lock cylinder, a tumbler unit comprising a carrier having spaced end walls connected by a side wall, a plurality of tumblers disposed in the space between the end walls with one side edge engaging the side wall, sliding connections between the tumblers and the side wall to guide the tumblers for endwise movement, and longitudinal ribs on the tumblers in sliding engagement to co-act with the sliding connections between the tumblers and the carrier side wall and hold the tumblers properly spaced apart, the combined thickness of the tumblers at their longitudinal ribs substantially spanning the distance between the end walls of the carrier. 20 90
- 25 17. In a tumbler lock, a die cast lock cylinder having a tumbler receiving aperture, a plurality of tumblers disposed in said aperture, and a sheet metal side wall at each side of the plurality of tumblers to hold the side edges of the tumblers out of contact with the walls of the aperture in the die cast lock cylinder. 30 95
- 30 18. In a tumbler lock, a die cast lock cylinder having a tumbler receiving aperture, a plurality of tumblers disposed in said aperture, and a sheet metal side wall at each side of the plurality of tumblers to hold the side edges of the tumblers out of contact with the walls of the aperture in the die cast lock cylinder, one of said side walls having a connection with each of the tumblers to maintain the tumblers assembled as a unit and retain the same in the lock cylinder. 100 100
- 40 19. In a key controlled tumbler lock, a die cast lock cylinder having a tumbler receiving aperture, a plurality of tumblers disposed in said aperture, a sheet metal side wall at each side of the plurality of tumblers to hold the side edges of the tumblers out of contact with the walls of the aperture in the die cast lock cylinder, one of said side walls having a connection with each of the tumblers to maintain the tumblers assembled as a unit and retain the same in the lock cylinder, and means on the other side wall to form a guide and support for the key. 105 110
- 45 20. In a key controlled tumbler lock, a die cast lock cylinder having a tumbler receiving aperture extending transversely therethrough, a plurality of tumblers disposed in said aperture a sheet metal side wall at each side of the plurality of tumblers to hold the tumblers out of contact with the walls of said aperture, means to connect said side walls, a guiding and retaining connection between each tumbler and one of the side walls, and means on the other side wall forming a guide and support for the key. 115 120
- 50 21. In a key controlled tumbler lock, a lock cylinder having a transverse tumbler receiving aperture, tumblers in said aperture, each of said tumblers having a key receiving recess opening 75 to one side thereof, sheet metal side walls at 125 130
- 55 the opposite side edges of the tumblers to hold the tumblers out of contact with the walls of the aperture, a guiding and retaining connection between each of the tumblers at their unrecessed sides and the adjacent side wall, and a longitudinal flange on the other side wall projecting into the key receiving recesses of the tumblers to guide and support a key insertable into said recesses. 135 140
- 60 22. In a key controlled tumbler lock, a lock cylinder having a tumbler receiving aperture, locking tumblers in said aperture, a first side wall positioned between the tumblers at one side edge and the adjacent side wall of the aperture, a sliding guiding and retaining connection between said side wall and the adjacent edges of the tumblers, whereby the tumblers are held spaced apart and guided for individual longitudinal movement, expansive springs for the tumblers disposed in the spaces between adjacent tumblers and confined between abutments on the tumblers and abutments on said side wall, and a second side wall disposed between the opposite side edges of the tumblers and the adjacent wall of the aperture to maintain said other side edges of the tumblers out of contact with said wall of the aperture and retain the tumblers operatively engaged with the first side wall. 145 150
- 65 23. In a tumbler lock, a lock cylinder having a transverse tumbler receiving aperture, a tumbler unit removably received in said aperture and comprising spaced side walls connected by spaced end walls to form a rectangular frame, a plurality of tumblers confined in said frame, and a connection between each of the tumblers and one side wall to guide the individual tumblers for independent longitudinal movement between defined limits, whereby the tumblers are held assembled with said frame, said side walls engaging abutments in the adjacent walls of the lock cylinder aperture to properly locate the 155 160
- 70 24. In a tumbler lock, a lock cylinder having a transverse tumbler receiving aperture, a tumbler unit removably mounted in said aperture comprising, a pair of spaced side walls, a plurality of tumblers between the side walls, said tumblers having key receiving recesses, means to connect the side walls to hold the same against relative movement parallel to the longitudinal axes of the tumblers, individual springs for the tumblers confined between abutments on the tumblers and abutments on one of the side walls, and a guide carried by the other side wall and extending into the key receiving recesses of the tumblers to guide and support a key whereby the proper positioning of the key is accomplished entirely within the tumbler unit and independent of the lock cylinder. 170 175
- 75 25. In a tumbler lock, a lock cylinder having a tumbler receiving aperture, a tumbler unit in said aperture comprising, a plurality of locking tumblers, a tumbler carrier having spaced end walls connected by a side wall, means to retain the tumblers operatively assembled with said carrier, a side plate extending across the open side of the carrier and stationary in said tumbler receiving aperture, an interlocking connection between each end wall of the carrier and the stationary side plate whereby the carrier is held against all relative movement with respect to the 180 185
- 80 side plate except endwise shifting of the carrier parallel to the major axis of the lock cylinder, and an interlocking connection between the tumblers and said stationary side plate whereby the tumblers and the carrier are restrained 190 195

against endwise shifting except when the tumblers are retracted by the insertion of a proper key.

26. In a key controlled tumbler lock, a lock cylinder having a tumbler receiving aperture, a plurality of tumblers in said aperture, a side plate disposed between one side of the tumblers and the adjacent wall of the tumbler receiving aperture, said tumblers being retractable to inoperative position by a proper key and being shiftable 5 in unison for the purpose set forth, means on said side plate and engaging the locking tumblers to prevent such shifting except when all of the tumblers are completely retracted by a proper key, and means on said side plate forming a guide 10 and support for the key to insure a definite position of the key with respect to the means for preventing the shifting of the tumblers so that only the proper key will free the locking tumblers for shifting.
- 20 27. In a key controlled tumbler lock including a lock cylinder having a tumbler receiving aperture, a tumbler unit in said aperture including an auxiliary tumbler, and means requiring bodily shifting of the other tumblers towards the auxiliary tumbler to free the auxiliary tumbler for retraction, and a single member to restrain such shifting of said other tumblers except when said other tumblers are fully retracted and to support and guide the key required to effect complete 25 retraction of said other tumblers.
28. In a key controlled tumbler lock including a lock cylinder having a tumbler receiving aperture, a tumbler unit in said aperture comprising a plurality of tumblers, the retraction of one of 30 which requires bodily shifting of the other tumblers in a direction at an angle to the normal locking and unlocking movements of the tumblers, a member having comb teeth projected into the spaces between said shiftable tumblers to hold 35 said tumblers against shifting, and said shiftable tumblers having notches to be aligned with said comb teeth upon retraction of said shiftable tumblers to inoperative positions by a proper key to free said shiftable tumblers for the required shifting 40 movement.
29. In a tumbler lock, a lock cylinder having a transverse tumbler receiving recess, a tumbler mounted in said recess to be moved longitudinally to and from a position having one end projecting 45 beyond the cylindrical wall of the cylinder and flatwise in a direction parallel with the axis of the cylinder during the unlocking of the lock, an abutment engageable with said tumbler to hold the same against flatwise movement as long 50 as the tumbler is in any position other than fully retracted within the body of the cylinder, and the tumbler having a notch to be aligned with said abutment upon retraction of the tumbler to an inoperative position within the cylinder to free 55 the tumbler for flatwise movement.
30. A tumbler for locks comprising, a substantially flat plate having a large recess opening to one side edge to divide the tumbler into spaced end portions, connected by a medial portion and 60 having a notch in one of its end portions, the recess being adapted to receive a key and the notch being adapted to permit the passage therethrough of a restraining abutment to free the tumbler for flatwise movement.
31. In a key controlled tumbler lock including 65 a plurality of tumblers, each having a key receiving recess opening to one side and a notch in an unrecessed portion of the tumbler and opening to the same side at which the recess opens, 70 a member disposed along said side of the tum-

blers to which the recesses and notches open, a plurality of abutments on said member engaging the tumblers to hold the same against flatwise shifting, said abutments being passable through the notches in the tumblers when the tumblers are retracted to their inoperative positions by a proper key, and means on said member to guide and support the key to insure proper alignment of the notches with the abutments.

32. In a tumbler lock having a lock cylinder, a tumbler in said lock cylinder, a holding member engaged with the tumbler to prevent its retraction, said holding member being movable to free the tumbler for retraction, and key controlled means to prevent movement of the holding member.

33. In a tumbler lock including a lock cylinder having a tumbler receiving aperture, a tumbler in said aperture movable transversely of the lock cylinder to and from an operative position with one end projecting from the lock cylinder, a holding member in said aperture normally engaged with said tumbler to hold the same in its projected operative position, said holding member being movable toward the tumbler to free the tumbler for retraction from its operative position, and key controlled means to prevent such movement of the holding member.

34. In a tumbler lock including a lock cylinder having a tumbler receiving aperture, a tumbler mounted in said aperture for transverse movement to and from an operative position projecting one end beyond the cylindrical wall of the lock cylinder, a member slidably mounted in the aperture for movement toward and away from said tumbler, means on said member engaging the tumbler to hold the same in its operative projected position, said member being movable by a proper key to free the tumbler for retraction from its operative position and said tumbler being engageable by the key to be retracted upon movement of said member by the key, and means to prevent movement of said member, said last named means being disabled by the key.

35. In a tumbler lock including a lock cylinder having a tumbler receiving aperture, an auxiliary tumbler mounted in said aperture for movement transversely to the axis of the lock cylinder to and from an operative projected position, a member slidably disposed in the aperture for movement toward and away from said auxiliary tumbler in a direction substantially parallel to the major axis of the lock cylinder, means carried by said member and engaging the auxiliary tumbler to hold the auxiliary tumbler in its operative projected position when said member is in one position of movement, movement of said member to another position releasing the auxiliary tumbler for retraction, and a plurality of primary tumblers connected with said member and operable in their normal positions to prevent movement of said member, said primary tumblers being retractable to free the member for movement by a proper key, and said member and auxiliary tumbler being respectively movable and retractable by said same key.

36. In a tumbler lock including a lock cylinder having a transverse aperture for the reception of tumblers, an auxiliary tumbler mounted in one end of the aperture for movement to and from an operative position projecting one end out of the aperture, a tumbler pack slidably in the aperture toward and away from said auxiliary tumbler and comprising a carrier having

- spaced end walls connected by a side wall and a plurality of primary tumblers assembled in said carrier, a cam projected from one end wall of the carrier to engage in an opening in the auxiliary tumbler and hold the auxiliary tumbler in its projected operative position when said carrier is at one limit of movement and freeing the auxiliary tumbler for retraction upon movement out of said position, and means fixed with respect to the lock cylinder and engaged with the primary tumblers requiring complete retraction of said primary tumblers to free the carrier for such movement. 80
37. In a tumbler lock including a lock cylinder, an auxiliary tumbler transversely movable in said lock cylinder, a tumbler pack movable endwise in said lock cylinder toward and away from the auxiliary tumbler and comprising a carrier and a plurality of primary tumblers each individually yieldably projected to operative position, a connection between said auxiliary tumbler and the tumbler pack, whereby bodily endwise movement of the tumbler pack toward the auxiliary tumbler is necessary to free the auxiliary tumbler for retraction, and means to prevent endwise movement of the tumbler pack except when the primary tumblers comprising the pack are retracted, said primary tumblers 86

- being retractable by a proper key inserted therethrough to free the pack for movement, and the auxiliary tumbler being retractable by the nose of the key which projects from the tumbler pack into engagement with the auxiliary tumbler. 80
38. In a tumbler lock including a lock cylinder, an auxiliary tumbler mounted in the lock cylinder for transverse movement to and from an operative position projecting one end beyond the cylindrical surface of the lock cylinder, a tumbler pack movable endwise in the lock cylinder toward and away from said auxiliary tumbler and comprising a plurality of primary tumblers and a carrier to hold the primary tumblers assembled, means to yieldably urge the pack away from the auxiliary tumbler, a cam carried on said carrier and engaged with the auxiliary tumbler to move the auxiliary tumbler to its operative projected position upon movement of the pack under influence of the yieldable means and to hold the auxiliary tumbler in its operative projected position as long as the pack is in its normal position to which it is urged by the yieldable means, and means to lock the pack in said normal position to which it is moved by the 100 yieldable means. 96
- EDWARD N. JACOBI.
